UNITED STATES PATENT OFFICE.

WILLIAM H. BANZETT, OF BERGENFIELD, NEW JERSEY, ASSIGNOR TO AMERICAN LITHOGRAPHIC COMPANY, OF NEW YORK, N. Y., A CORPORATION OF NEW YORK.

OFFSET-PRINTING MACHINE.

1.162.739.

Specification of Letters Patent. Patented Dec. 7, 1915.

Application filed September 5, 1914. Serial No. 860,388.

To all whom it may concern:

Be it known that I, WILLIAM H. BANZETT,
a citizen of the United States, and a resi-
dent of Bergenfield, in the county of Bergen
5 and State of New Jersey, have invented cer-
tain new and useful Improvements in Offset-
Printing Machines, of which the following
is a specification.

This invention relates to rotary printing machines and particularly to that class thereof which employs a plurality of design cylinders, and a cylinder to which the designs are transferred and from whence printed on the sheet or web in coaction with an impression cylinder.

The object of my improvements is to provide a machine of the class specified combining large length of sheet capacity with minimum height and length of machine, and ample accessibility of design and transfer cylinders.

This invention presents a machine wherein the thrust on the transfer cylinder exerted by the design cylinders is in a direction away from the impression cylinder. The thrust exerted on the transfer cylinder by the two design cylinders and the impression cylinder, or any combination of these, is always in the same general direction, thus reducing to a minimum the variations in pressure on the blanket of the transfer cylinder. It is highly desirable, in this delicate method of printing, that the pressure on the yielding blanket of the transfer cylinder be as invariable as possible for the production of clear, sharp impressions.

With these ends in view my improvements comprise features illustrated in their preferred embodiment in the drawing accompanying this specification wherein the figure represents in diagrammatic form a side elevation of a printing machine embodying my improvements.

My improvements include particularly
45 four cylinders of equal diameter, comprising
an impression cylinder 2, a transfer cylinder 3 in coacting relation therewith, and
two design cylinders 4 and 5 in printing relation
50 with said transfer cylinder, all arranged
relatively to each other to afford
maximum efficiency of coaction and production
in combination with minimum space
occupied.

Printing machines of the class to which
55 my improvements pertain are commonly

known as offset printing machines, as the design or designs carried by cylinders 4 and 5 are offset, in different colors or in one color, onto transfer cylinder 3 and thence printed onto the sheet fed between said transfer cylinder and impression cylinder 2. 60

While this general method of procedure is well known in the art, all machines for accomplishing this result which are known to me are prodigal of space, particularly in height, and the several cylinders are so arranged as to afford inadequate access to the surfaces of the design and transfer cylinders for cleaning, changing plates and so forth. By my improved arrangement, these objections and difficulties have been overcome and I have produced a machine of greater capacity of product in size and quantity, of greater economy in time of make ready and productive of a finer quality of printing, than in any machine heretofore known to me.

Design cylinders 4 and 5 are provided with the inking mechanisms of well known character indicated in a general way by 6 and 7 respectively, and, if the machine is 80 to be used for lithographic printing, dampening mechanisms 8 and 9 respectively may be employed.

Sheet feeding means, comprising feed board 10 and sheet stop 11, are disposed contiguous to impression cylinder 2, opposite transfer cylinder 3. Said impression cylinder 2 may be provided with the usual clips as 12 for gripping the leading end of the sheet delivered thereto. Design cylinders 4 and 5 are disposed on opposite sides respectively of and in printing relation with said transfer cylinder. Also the common plane of the axes of cylinders 2 and 3 is preferably horizontal and the common plane of the axes of the design cylinders is substantially normal thereto. By this arrangement design cylinder 4 is above transfer cylinder 3 and design cylinder 5 is below said transfer cylinder. Also the common axial plane of design cylinders 4 and 5 intersects the common axial plane of impression and transfer cylinders 2 and 3 respectively, between the axis of the transfer cylinder and the line of contact of that cylinder with the impression cylinder. By this arrangement maximum accessibility to said transfer cylinder is afforded and from the same end of the machine (the left hand end in the figure) large accessibility to the de- 11

sign cylinders is afforded. Also the inking and dampening mechanisms for both the design cylinders are accessible from both left and right hand ends of the machine.

5 Take off means which may comprise sprockets 13 and 14, and gripper chains as 10 15, are provided below said feed board 10 in operative relation to said impression cylinder 2. Said take off means are effective 10 for taking the printed sheet from impression cylinder 2 and delivering it printed side up to table 16. No means for moving cylinders 4, 3 and 5 toward and from each other are illustrated as such means are 15 well known and do not pertain to the present improvements.

I claim:

1. A two-color planographic offset press comprising a transfer cylinder, an impression cylinder and two design cylinders 20 25 engaging the transfer cylinder in such positions that the thrust exerted on the transfer cylinder by the design cylinders and the impression cylinder is in the same general direction.

2. An offset printing machine including in combination four cylinders of equal diameters comprising an impression cylinder and a transfer cylinder in coacting relation, 30 35 the common axial plane of said impression and transfer cylinders being substantially horizontal, a design cylinder above and a design cylinder below said transfer cylinder each on a fixed axis in printing relation with said transfer cylinder, the common axial plane of said design cylinders being substantially normal to the common axial plane of the impression and transfer cylinders, means for inking and means for dampening said design cylinders, sheet feeding means contiguous to said impression cylinder and opposite to said transfer cylinder, and take off means below said sheet feeding means in operative relation to said impression cylinder.

3. An offset printing machine including in combination four cylinders of equal diameters comprising an impression cylinder and a transfer cylinder in coacting relation 50 55 and two design cylinders on opposite sides respectively of and in printing relation with said transfer cylinder, the axial plane of said design cylinders intersecting the axial plane of the impression and transfer cylinders between the axis of the transfer cylinder and the line of contact of that cylinder with the impression cylinder.

4. An offset printing machine including in

combination four cylinders of equal diameters comprising an impression cylinder and a transfer cylinder in coacting relation, the common axial plane of said impression and transfer cylinders being substantially horizontal, and a design cylinder above and a design cylinder below said transfer cylinder 60 65 each in printing relation with said transfer cylinder, the axial plane of said design cylinders intersecting the axial plane of the impression and transfer cylinders between the axis of the transfer cylinder and the line of contact of that cylinder with the impression cylinder.

5. An offset printing machine including in combination four cylinders of equal diameters comprising an impression cylinder 70 75 and a transfer cylinder in coacting relation and two design cylinders on opposite sides respectively of and in printing relation with said transfer cylinder, the common axial plane of said design cylinders being substantially normal to the common axial plane of the impression and transfer cylinders, and the axial plane of said design cylinders intersecting the axial plane of the impression and transfer cylinders between the axis 80 85 of the transfer cylinder and the line of contact of that cylinder with the impression cylinder.

6. An offset printing machine including in combination four cylinders of equal diameters comprising an impression cylinder and a transfer cylinder in coacting relation, the common axial plane of said impression and transfer cylinders being substantially horizontal, and a design cylinder above and 90 95 a design cylinder below said transfer cylinder each in printing relation with said transfer cylinder, the common axial plane of said design cylinders being substantially normal to the common axial plane 100 of the impression and transfer cylinders, and the axial plane of said design cylinders intersecting the axial plane of the impression and transfer cylinders between the axis of the transfer cylinder and the line of contact of that cylinder with the impression cylinder.

Signed at New York, in the county of New York and State of New York, this 1st day of September, 1914, before two subscribing witnesses.

WILLIAM H. BANZETT.
